UNITED STATES PATENT OFFICE.

JAMES W. DUFFY, OF DRUMRIGHT, OKLAHOMA.

AUTOMATIC PIPE-VISE.

1,261,723.

Specification of Letters Patent. Patented Apr. 2, 1918.

Application filed December 18, 1916. Serial No. 137,646.

To all whom it may concern:

Be it known that I, JAMES W. DUFFY, a citizen of the United States, residing at Drumright, in the county of Creek and State of Oklahoma, have invented certain new and useful Improvements in Automatic Pipe-Vises, of which the following is a specification.

The present invention has reference generally to improvements in a vise and more particularly relates to an automatic pipe vise.

As the primary aim and object, it is contemplated by the present invention to provide a vise embodying a yieldingly mounted wheel jaw and manually adjustable yet rigid jaw, the jaws coöperating with each other for automatically engaging the pipe subsequent to the arranging of a pipe therebetween, to consequently enable a plumber, mechanic, or the like to effectively work upon the pipe or other object held by the jaws.

It is an equally important object of the present invention to so construct the supporting frame in order to effectively accommodate the body of the wheel jaw, and guide the movement of the wheel jaw.

More particularly, the present invention embraces the provision of novel means for limiting the outward movement of the wheel jaw; to provide novel means for yieldingly mounting the wheels in the body of the wheel jaw.

Among the other aims and objects of the present invention may be recited the provision of a device of the character mentioned and in which the number of parts are few, the construction simple, the cost of production low, and the efficiency high.

Other improvements and novel details in the construction and arrangement of the various parts of the device will be brought out more in detail in the description to follow, which, for a clear understanding of the invention, should be considered in connection with the accompanying drawings forming a part thereof and wherein is disclosed for the purpose of illustration, a convenient and satisfactory embodiment of the invention.

It is to be noted, in this connection, that minor changes in the construction and arrangement of the parts may be made without departing from the spirit of the invention, or principle of the operation of the various parts.

The preferred embodiment of the invention is clearly illustrated in the accompanying drawings, in which:

Figure 1 is a side elevation of my invention.

Fig. 2 is a horizontal section partly in top plan taken on line 2—2 of Fig. 1 in the direction in which the arrows point.

Fig. 3 is a vertical longitudinal section partly in elevation.

Fig. 4 is a transverse section taken on line 4—4 of Fig. 1 in the direction in which the arrow points.

Fig. 5 is a transverse section partly in elevation and is taken on line 5—5 of Fig. 3.

Referring now, more particularly, to the accompanying drawings, I provide my improved vise comprising a support which in the present instance embodies an attaching base 1 adapted to be rigidly mounted on a suitable main support through the medium of fastening devices 2. Formed integral with the upper face of the base is a substantially U-shaped supporting frame 3 the lower portion of the frame being longer than the upper portion and extending throughout the length of the base. The adjacent faces of the upper and lower portions of the frame are provided with longitudinal grooves 4 and 5 while the inner faces of the respective side walls of each of the grooves are provided with opposed racks 6 and 7 for a purpose that will presently appear. Vertical bars 8 are formed integral with the outer edges of the upper and lower portions of the frame 3 and serve to brace these portions of the frame adjacent the outer ends.

Slidably mounted in the frame is my improved wheel jaw which in the present instance consists of a body 9. The upper and lower ends of which are reduced so that the extreme free ends are arranged in close relation with the bottom of the grooves 4 and 5 while the shoulders 10 are formed where the body is reduced and ride upon the adjacent faces of the side portions of the frame 3. The body 9 has its front end bifurcated to provide a recess 11 while the side portions provided by the bifurcation and resting upon the adjacent faces of the side portions of the frame are also bifurcated to provide recesses 12 for a purpose to be described. A pair of wheels 13 having serrated peripheries 14 are carried by stub shafts 15 arranged concentrically therethrough. The respective ends of

the stub shafts are journaled in opposed horizontal slots 16, and when the stub shafts are in position the wheels will be arranged one above the other in the recess 11 as indicated in the drawings. Gear wheels 17 are carried by the stub shafts and by the opposite faces of each of the wheels 13 and are engageable with the racks 6 and 7 during the sliding movement of the body 9. In order to normally hold the respective ends of the shafts 15 toward the outer ends of the slots I employ leaf springs 17' and mount the same in the recesses 12 by means of the pins 18 which extend in through the walls of the recesses, the springs having their respective ends bearing against the adjacent ends of the stub shafts 15 as indicated in Figs. 1 and 4.

With a view toward providing suitable means for yieldingly mounting the wheel jaw, I employ a coil spring 19 and arrange the respective ends in the recess 20 in the rear edge of the body and in a recess 21 in the intermediate portion of the U-shaped frame. Suitable means such as knob screw 22 is removably engageable with the body 9 and co-acts with the adjacent vertical bar 8 for limiting the outward movement of the movable wheel jaw.

30 Coöoperating with the wheel jaw is my improved adjustable yet rigid jaw. In the present instance this jaw consists of a vertical upright hollow body 23 the jaw face of which is provided with a recess 24 while 35 the lower side walls of the body are provided with opposed grooves 25 so that the body is slidably mounted on the long lower portion of the support 3 as indicated in Fig. 5. This latter mentioned portion is provided on its 40 upper face with teeth 26 while a pawl 27 is pivotally mounted in the jaw by means of transversely extending fastening devices 28. A handle 29 is offset from the shank 30 of the pawl while a leaf spring 31 is arranged 45 in a recess 32 in the pawl and rigidly connected to the shank by means of suitable fastening devices 33. The outer end of the spring bears against a lug 34 which depends from the top of the body 23 and as is apparent 50 the spring normally holds the pawl in engagement with the teeth 26 and when it is desired to adjust this jaw it is only necessary to press the handle 29 inwardly and consequently release the pawl to permit of 55 the jaw being adjusted to a predetermined position. Subsequent to adjustment the handle is released whereupon because of the action of the spring the pawl engages the teeth 26 and maintains the movable jaw in a 60 substantially rigid position on the frame.

The operation of this invention may be reviewed as follows:—

As illustrated in the drawings the vise is in an inoperative position, the set screw 22 65 coöoperating with one of the bars 8 to limit

the outward movement of the wheel jaw. However, by engaging this set or knob screw 22 and sliding the body 9 against the tension of the spring 19 a pipe may be arranged against the jaw face 24 whereupon the screw 70 22 is released to consequently allow the spring 19 to automatically move the wheels into engagement with the pipe in a manner that the wheels 13 will coöperate with the jaw face 24 to effectively hold the pipe. It 75 is also to be understood preparatory to this arrangement that the jaw 23 is adjusted on the frame by pressing the handle 29 against the tension of the spring 31 and releasing the handle subsequent to the adjustment. When a turning movement is imparted to the pipe (not shown), and assuming that the movement is directed upwardly toward the upper wheel 13, the lower wheel 13 will tend to rotate, and the rack 7 will be 80 engaged by the teeth of the adjacent gear wheels 17. The lower stub shafts will then move against the tension of the lower ends of the spring 17'. During this movement the upper wheel 13 will be caused to rotate 85 in the direction indicated by the arrow and will cause the gear wheel to move outwardly on the rack 6. As the adjacent stub shaft 15 is at the outer end of the slot 16, the body 90 will move outwardly to a slight extent and cause one or the other of the wheels to bitingly engage the pipe. As is apparent, this action is automatic and effectively serves to retain the pipe in position. Of course if the turning movement is imparted in an opposite direction the operation will be reversed, that is, the upper wheel will be moved rearwardly, the shaft 15 moving 100 through the slot while the lower wheel will move the body outwardly to a slight extent 105 since the spring 17' normally holds the stub shafts adjacent the outer ends of the slots 16.

As many changes could be made in the above construction and many apparently widely different embodiments of this invention could be made without departing from the scope thereof, it is intended that all matter contained in the above description or shown in the accompanying drawings shall be interpreted as illustrative and not in a 110 limiting sense. It is also to be understood that the language used in the following claims is intended to cover all of the generic and specific features of the invention herein described and all statements of the scope of 115 the invention, which, as a matter of language, might be said to fall therebetween.

Having thus described my invention, what I claim as new and desire to secure by Letters Patent is:—

1. An automatic pipe vise including a supporting base, a substantially U-shaped frame integral therewith and having the lower portion longer than the upper portion and arranged substantially parallel to the base, a 130

jaw slidably including a body mounted in the frame, a pair of superposed wheels rotatably mounted in the jaw and slidable in the body, and resilient means mounted in the body for normally holding the wheels toward the outer end of the body, other resilient means interposed between the body and the frame for actuating the body and its wheels, means engageable with the body and coöoperating with the frame for limiting the outward movement of the body and for facilitating adjustment of the body, and a manually adjustable and substantially rigid jaw mounted on the long portion of the frame and coöoperating with the wheels.

2. An automatic pipe vise including a base, a substantially U-shaped frame integral with the base and having the lower portion longer than the upper portion and arranged substantially parallel with respect to the base, the adjacent faces of the upper and lower portions of the frame being provided with longitudinal grooves, the sides of the grooves being recessed and provided with racks, a jaw body slidably mounted in the frame and having one end bifurcated to provide a recess, the side portions adjacent the

recess being bifurcated, and the portions to the side of the recess being also provided with opposed pairs of horizontal slots, stub shafts mounted in the slots, wheels carried by the stub shafts and arranged one above the other, and within the first mentioned recess and in the grooves, gear wheels carried by the opposite faces of the wheels and by the shafts and also engageable with the racks, resilient means mounted in the body for normally holding the stub shafts toward the outer ends of the slots, a coil spring interposed between the body and one end of the frame for yieldingly supporting the body, means for limiting the outward movement of the body, and a manually operable yet substantially rigid jaw mounted in the long portion of the frame and positioned opposite to the wheels for coöperation therewith.

In testimony whereof I affix my signature in presence of two witnesses.

JAMES W. DUFFY.
